UNITED STATES PATENT OFFICE.

JOSEF ELLMAUER, OF MILWAUKEE, WISCONSIN, ASSIGNOR, BY MESNE ASSIGNMENTS, TO REFRIGO CORPORATION, OF MILWAUKEE, WISCONSIN, A CORPORATION OF WISCONSIN.

REFRIGERATING APPARATUS.

1,369,734.

Specification of Letters Patent. Patented Feb. 22, 1921.

Application filed October 27, 1919. Serial No. 333,811.

To all whom it may concern:

Be it known that I, JOSEF ELLMAUER, a citizen of the United States of America, residing at Milwaukee, in the county of Milwaukee and State of Wisconsin, have invented certain new and useful Improvements in Refrigerating Apparatus, of which the following is a specification.

The primary object of the invention is the provision of a combined compressor and condenser of compact form adapted for employment in a refrigerating plant and having a water cooling system for both of the primary elements of the machine.

15 A further object of the invention is to provide a compressor and condenser for the refrigerating fluid of a plant, combining these two machines in a single compact structure that is comparatively easy and in-

20 expensive to manufacture in any desired size or capacity to suit the requirements of the installation, the structure providing a more economical machine performing all the functions of a separate compressor and condenser

25 as ordinarily positioned in the pipe line of a refrigerating system between the expansion coils and the expansion valve.

With these general objects in view the invention consists of the novel combination 30 and arrangement of parts hereinafter more fully described in connection with the accompanying drawings and in which like reference characters designate corresponding parts throughout the several views.

35 In the drawings,

Figure 1 is a side elevational view of the invention and

Fig. 2 is a vertical central sectional view thereof.

40 Referring more in detail to the drawings, my machine consists of an upright casing 10 having a centrally positioned compressor cylinder 11 therein with the lower portion of the casing 10 constituting the crank case

45 of the compressor with the reciprocating piston 12 of said cylinder connected by rod 13 to the crank shaft 14 journaled through the chamber 15 of the crank case. The casing 10 is mounted upon a suitable base 16, being secured thereto by stud bolts 17 while

50 a pulley wheel 18 carried by the outwardly projecting end 19 of the crank shaft 14 is connected by a belt 20 to the power pulley

21 of a suitable motor, such as the electric motor 22 also mounted upon the base 16. 55

The refrigerating fluid coming from the expansion coils of the refrigerating plant enters a scale separator 23 by means of a pipe 24. The separator 23 is preferably formed integral with a receiver 25 positioned therebeneath, the combined separator and receiver being firmly secured to one side of the casing 10. A water conduit 26 passes horizontally through the chamber 27 of the receiver 25 the cooling water being admitted 60 by an inlet pipe 28. The water flows through the conduit 26 to an annular water space 29 surrounding the compressor cylinder 11, a passage 30 in the side of the casing 10 registering with the conduit 26 admitting 65 water into a side portion 31 of the cooling chamber 29.

An outlet pipe 32 in the detachable top 33 of the casing 10 affords means for conducting the water from the chamber 29 it being 70 understood that the cooling water is adapted to be circulated in any usual manner. An annular condenser chamber 34 for the refrigerant operated upon by the compressor surrounds the water chamber or cooling 75 jacket 29 of the machine, this condenser chamber being connected to the receiver chamber 27 by registering ports 35 and 36 in corresponding side portions of the casing 10 and receiver 25 respectively. The compressed and condensed refrigerant leaves the receiver chamber 27 to the expansion valve, 80 not shown, through a pipe 37 at one side of the machine, the conduit 26 serving to cool the refrigerant within the chamber 27. 90

A tubular screen 38 in the chamber 39 of the scale separator 23 extends between the top plate 40 of the separator and an outlet nozzle 41 for the refrigerant axially projecting upwardly within the separator 23. The 95 refrigerant from the expansion coil passes through the pipe 24 into the separator chamber 39 and through the screen 38 into the nozzle 41, the latter communicating with the conduit 42 in the side of the casing 10 and 100 passing through the condenser chamber 34 to an annular intake chamber 43 surrounding the lower portion of the cylinder 11 and surrounded by the cooling jacket 29. Ports 44 in the wall of the cylinder 11 admit the 105 refrigerant from the intake chamber 43 to

the cylinder 11 when the piston 12 is at the lower extremity of its stroke while one or more similar ports 45 in the cylinder 11 are uncovered by the piston 12 when elevated 5 for admitting the refrigerant into the crank chamber 15.

A block 46 secured to the upper end of the cylinder 11 has a slidably mounted head 47 for the upper end of the cylinder 11 movable 10 within a chamber 48 of said block 46, while a spring 49 bears upon the head 47 normally maintaining the same in its closed position upon the cylinder 11.

A relief valve 50 in the top of the piston 12 is normally held closed by a spring 51 and adapted for opening during the downward stroke of the piston 12 for admitting refrigerant to the cylinder 11 above the piston and thereby relieving a tendency toward 20 the creating of a vacuum by the descending piston. The compressed refrigerant leaves the cylinder block 46 through a passage 52 and passes by means of a pipe 53 through the cooling chamber 29 outwardly of the 25 top 33 of the casing 10 and thence to the annular chamber 54 in the upper portion of an oil separator 55 secured to the casing 10 at the opposite side thereof from the separator receiver, 23, 25.

30 Any oil in the refrigerant may pass through a port 56 into a central bore 57 of the separator 55 and into the bottom chamber 58 thereof to be readily removed by detaching the bottom plug 59 of the separator 35 55. The refrigerant passes from the chamber 54 through registering ports 60 and 61 in the adjacent sides of the separator 55 and casing 10 respectively and enters the condenser chamber 34 in its compressed condition 40 for cooling by the water jacket 29. The passing of the refrigerant outwardly of the condenser chamber 34 through the receiver chamber 27 and the pipe 37 to the expansion valve has been already noted.

45 An indicator 62 upon the top 40 of the scale separator 23 denotes the pressure of the incoming refrigerant from the expansion coils, while a similar indicator 63 centrally of the top of the oil separator 55 in 50 communication with the bore 57 thereof by the T-fitting 53' shows the degree of pressure that has been placed upon the refrigerant by the piston 12 and ready for condensation and passing through the expansion valve. A stuffing box 64 is preferably provided in the casing top 33, for the outlet pipe 53 of the refrigerant. Stud bolts 65 may be provided for securing the top 33 upon the casing 10 while a removable plate 55 60 9 may be provided at the side of the casing 10 for convenience in obtaining access to the interior working parts of the machine.

The complete operation of the invention 65 will be fully understood from this detailed description thereof, the compressor inclosed

within the condenser and a single water jacket for cooling both the compressor and condenser being of primary importance, while the scale separator with its receiver for the outgoing refrigerant is a further advantageous arrangement as well as the oil separator 55 oppositely positioned with respect thereto. The normally closed valve 50 of the piston 12 relieving any vacuum in the cylinder 11 has in coöperation the supplying of refrigerant through the port 45 to the crank chamber 15 to replace the refrigerant taken out of the crank case through said relief valve 50. The motor 22 being automatically controlled for operating 70 the piston 12 when it is desired to start the circulation of the refrigerant, the manner of circulating the refrigerant for the refrigerating system will be apparent, the degree of compression attained by the compressor depending somewhat upon the force of the piston 12 compared with the strength of the spring 49 in normally maintaining the cylinder head 47 closed.

75 While the form of the invention herein is believed preferable, it will be understood that minor changes may be made therein without departing from the spirit and scope of my invention.

80 What I claim as new is—

1. A refrigerating apparatus comprising a casing having an axially positioned compression cylinder therein with the lower portion of the casing providing a crank chamber for the cylinder, an annular wall 100 surrounding the cylinder within the casing forming a condenser chamber between the wall and casing and a cooling chamber for both the condenser chamber and cylinder between said wall and cylinder, an operating piston within the cylinder and means of communication for the refrigerant between the cylinder and condenser chamber.

105 2. A machine comprising a chambered casing, a compressor cylinder within the casing, a wall around the cylinder forming an intake chamber for the refrigerant with sets of ports through the cylinder wall adapted for admitting refrigerant to the cylinder at different elevations and a reciprocating piston within the cylinder adapted for selectively closing said sets of ports, whereby refrigerant is alternately admitted into the cylinder above and below the piston during the operation of the compressor.

110 3. A refrigerating machine comprising a casing, a compressor cylinder centrally within the casing, an annular wall between the casing and cylinder forming a water cooling chamber for the cylinder and also 115 for the chamber between said wall and the casing, communicating means for the compressed refrigerant between the top of the casing and the said outer chamber, outlet and inlet pipes for the refrigerant carried 120 125 130

by the casing and outlet and inlet pipes for the cooling water.

4. A refrigerating machine comprising a casing, a compressor cylinder therein, a normally resiliently closed valve head for the cylinder, a reciprocating piston within the cylinder, a resiliently normally closed relief valve in the top of the piston adapted for opening during the downward stroke 10 of the latter whereby the refrigerant is admitted to the cylinder for compression during the return stroke of the piston.

5. A refrigerating machine comprising a casing, having an annular condenser chamber therein, a cylinder centrally within the casing forming a cooling jacket between the cylinder and condenser chamber, a reciprocating piston within the cylinder, communicating means between the cylinder and 20 condenser chamber, a combined scale separator and liquid receiver carried by the casing adapted to conduct the incoming and outgoing refrigerant therethrough and conducting means for the cooling water through 25 the liquid receiver in communication with the cooling jacket.

6. A machine comprising a casing, a compressor cylinder axially therein, a condenser chamber jacketed within the casing outwardly of the cylinder with a water cooling chamber therebetween, a block upon the cylinder having a chamber therein and an outlet passage from said block chamber, a head within the chamber of the block normally resiliently seated closed upon the top 30 of the cylinder, a reciprocating piston within the cylinder, a normally closed relief valve in the top of the piston and means for operating said piston.

40 7. A machine comprising a casing, a com-

pressor cylinder axially therein, a condenser chamber jacketed within the casing outwardly of the cylinder with a water cooling chamber therebetween, a block upon the cylinder having a chamber therein and an outlet passage from said block chamber, a head within the chamber of the block normally resiliently seated closed upon the top of the cylinder, a reciprocating piston within the cylinder, a normally closed relief valve in the top of the piston, means for operating said piston, an intake chamber surrounding the cylinder adapted to receive refrigerant from the expansion coils of the system and being in communication with the interior of the cylinder at different elevations for admitting refrigerant into the cylinder both above and below the piston during alternate reciprocations thereof, a casing at one side of the machine having a scale separator chamber in its upper end receiving the incoming refrigerant and being in communication with said intake chamber, the said side casing having a receiver in its lower portion communicating with the condenser chamber adapted for outletting the refrigerant to the expansion valve, an oil separator upon the casing communicating with the condenser chamber and a pipe communicating between the outlet passage of the block chamber and the interior of the oil separator, whereby the refrigerant passes through the scale separator to the compressor and thence through the oil separator to the condenser chamber and thence through the receiver to the expansion valve of the system.

In testimony whereof I affix my signature.

JOSEF ELLMAUER.
